UNITED STATES PATENT OFFICE

ALVIN H. WAAGE AND CLARENCE P. WAAGE, OF CHICAGO, ILLINOIS.

ELECTRIC SOLDERING-IRON.

979,904.

Specification of Letters Patent. Patented Dec. 27, 1910.

Application filed January 28, 1910. Serial No. 540,706.

To all whom it may concern:

Be it known that we, ALVIN H. WAAGE and CLARENCE P. WAAGE, citizens of the United States, residing in the city of Chicago, county of Cook, and State of Illinois, have invented new and useful Improvements in Electric Soldering-Irons, of which the following is a specification.

Our invention relates to improvements in heating devices in which heat is evolved by the application of an electric current.

One of the objects of our invention is to provide a heating device especially applicable for use as a soldering iron, curling iron, burnishing tool, and the like.

One of the specific objects of our invention is to provide in a device of the character adverted to, a structure of interchangeable, readily accessible parts that may be quickly assembled and when so assembled to form a substantial, durable tool.

Another object of our invention is to provide in a device of the character described a simple, interchangeable, heating element, or cartridge capable of being secured in place without the necessity of applying any stress or strain thereto to hold it in operative position, as when rotary screw-threaded parts are secured thereto.

Other and further objects of our invention will become readily apparent to persons skilled in the art from a consideration of the specification taken in conjunction with the drawings, wherein—

Figure 1 is an elevation of our device as applied to a soldering iron. Fig. 2 is a central longitudinal cross section of the same. Fig. 3 is an enlarged central longitudinal section of the heating element; and Fig. 4 is a detail showing an insulating terminal plug by which the electric terminals of the device are supported.

In all of the views, the same reference numerals indicate similar parts.

In the specific embodiment illustrated, 5 is a part to be heated, in this instance, a copper tip or point, having at its end the point 6, and hollow, as at 7, provided with a depression of less diameter coaxially therewith and extending farther toward the point, said tip being screw-threaded interiorly, as at 8.

9 is a hollow handle of insulating material, such as wood, rubber, or the like, provided on its end with a metal ferrule, 10, which is turned slightly over the end to pro-

tect the end surface of the insulating structure thereof. The handle is perforated with axial bores of three diameters, as at 11, 12, and 13.

An intermediate part composed of a metal tube, 14, is screw-threaded, as at 15, and carries upon its end a screw-threaded metal bushing, 16, for immediate screw-threaded engagement with the copper point, 5. The portion, 14, may be as long as desired. A metal cap, 16, is perforated as at 17, for the reception of the insulating terminal block, 18, and is screw-threaded, as at 19, for engagement with the tube, 14. The block 18 is circular in form, as at 20, for insertion within the tubular portion of the cap 16, being held emplaced therein by the pin 21 which takes through a perforation, 22, made in the insulating terminal block, 18. This pin-receiving perforation is shown as indicated in Fig. 4, at right angles to the position that it is shown to occupy in Fig. 2. It extends clear through the cylindrical part of the cap, 16, and is readily removable when the cap is taken from the handle. The insulating terminal block 18 is longitudinally perforated, as at 23—23', on each side of the squared portion, for the reception of the terminal wires that engage the screws, 24 and 24', which take through the reduced squared portions, 25, of the blocks 20, as clearly shown in Fig. 4, said screws affording terminal connecting means for the terminals 36—36' of the connecting wires, 26, 90 and the terminals 31'—33' of the heating element 27.

The heating element, 27, is composed of a copper rod or core, 28, extending through one end of the coil, 30, surrounding it, and at the other end provided with a circumferential groove, 29, the purpose of which will hereinafter be described. The coil, 30, is made up of a series of convolutions or turns of conducting wire, alternating in layers with strips of electric and heat resisting material, such as asbestos paper, mica, or the like. A single sheet of highly refractory material, such as sheets of mica or asbestos, is wound in the groove, 29, an electrical terminal wire 21 being placed over the paper so wound in the groove, and contact is made with the protruding end of the wire composing the coil, 30. A layer, 32, of binding wire is then wound over the conductor 31, and asbestos in the groove 29 so as to hold the terminal secure on the end of

the copper rod, 28. After the coil 30 has been entirely wound, in the manner described, the terminal wire, 33, is secured in the same manner over the end 29 of the rod 5 28 by means of other binding wire.

The cartridge, 27, is made up of a series of layers of wire, consisting of a number of convolutions and after this a layer of thin insulating material, such as asbestos paper.

- 10 The stem portion 35 is made up of a series of turns of asbestos paper, which is, preferably, a continuation of the first few turns of paper that is wound on the cartridge 27 proper. Before the extension, 35, of the 15 cartridge is completed, the terminal wires, 31 and 33, are laid adjacent the inner layers of paper and more paper is wound over them so as to completely embed said terminal wires in the insulated tube thus formed. The 20 various layers of paper may be cemented together by suitable cement for the purpose of holding the same in compact form.

The end 28 of the copper core is placed in the depression, 8, of the tip, 5, and the extension, 35, of the cartridge is passed through the tube 14. The handle 9 is slipped off of the threaded nipple or cap, 16, with which it has only frictional contact. The pin 21 may be taken out of the nipple part 17 and 25 the insulating block 20 and the terminal removed from the cap 16. The terminal wires, 31 and 33, are then passed through the perforations, 23 and 23', and the ends, 31' and 33', respectively are passed around the contact screws, 24—24'. The handle is then inserted over the end of the duplex wire 26 and wire terminals 36 and 36' of the wire 26 are bent around the screws, 24 and 24', and secured tightly thereto, thus completing 30 the circuit through the cartridge or heating element of the device, the handle being then slipped into position on the nipple or cap, 16. By this means a cartridge may be removed and a new one inserted in the device 35 in a very short time, and the parts may be reassembled without straining or in any way injuring or distorting the cartridge proper. If the end 28 of the cartridge core were threaded or the tip 5 screwed onto the end 50 of the threaded portion, an objectionable strain would be impressed upon the cartridge which would tend to clip the wires 31 and 33 and to disturb if not destroy the windings of the cartridge proper. The cartridge may be quickly removed and other cartridges of different resistance may be placed in lieu thereof to render the device readily adaptable for circuits of varying voltages.

60 What we claim is:

1. In a device of the character described,

a heating element or cartridge comprising a coil of wire, a heating conducting core upon which said coil is directly wound extending beyond the coil at one end for engagement with a part to be heated, a part to be heated provided with two bores, one for the coil and one for the core extension to make engagement therewith, a hollow handle, a pipe having a hollow enlarged end and connecting said handle and part to be heated, a terminal block supported in said enlarged end and projecting therefrom and over which the end of the handle is adapted to pass.

2. In a device of the character described, 75 a heating element or cartridge comprising a heat conducting core circumferentially grooved near one end, a coil surrounding said core leaving a part projecting at the other end, terminal wires overlying said 80 groove and secured by transversely wound securing wires, and an extension from said coil comprising a series of turns of relatively thin sheet insulating material embedding the terminal wires therein.

3. In a device of the character described, 85 a hollow part to be heated, a heating element therein having an insulating extension consisting of a roll of insulating sheet material integral with the insulation of said heating element, terminals of said heating element separated by layers and embedded within said roll, a tube through which said extension passes to the handle, an enlarged thimble or cap secured to the end of the tube, 95 a perforated insulating terminal block secured within said thimble and projecting therefrom, terminal screws carried by said projecting part of said block, and a longitudinally perforated handle to receive the conducting cord, and adapted to make engagement with and inclose said thimble.

4. In a device of the character described, 100 a tube 14 having screw-threaded engagement with a copper tip, 5, at one end and a cap, 16, larger than said tube at the other end, an insulating terminal block 18 projecting therefrom perforated, as at 23—23', for terminal wires, 31—33, said block adapted for support in said cap and flattened, as at 25, 110 and carrying terminal screws, 24—24', and a handle, 9, perforated axially, as at 11 and 12 providing a shoulder therebetween, and adapted for frictional engagement with said cap and limited in its movement by said 115 shoulder.

ALVIN H. WAAGE,
CLARENCE P. WAAGE.
